United States Patent Office

Des. 206,930
Patented Feb. 14, 1967

206,930

BELT

Zallo Loston, 113 S. Arnaz Drive,
Beverly Hills, Calif. 90211

Filed Feb. 23, 1966, Ser. No. 1,154

Term of patent 14 years

(Cl. D3—10)

FIG. 1 is a front perspective view of a belt showing my new design; and,

FIG. 2 is a back view thereof.

I claim:

The ornamental design for a belt, substantially as shown.
